UNITED STATES PATENT OFFICE.

ADAM E. KARSNER, OF NEW YORK, N. Y., ASSIGNOR TO EDWARD M. FOOTE AND ORVILLE G. WALES, OF SAME PLACE.

WRENCH.

SPECIFICATION forming part of Letters Patent No. 642,129, dated January 30, 1900.

Application filed June 24, 1899. Serial No. 721,744. (No model.)

To all whom it may concern:

Be it known that I, ADAM E. KARSNER, a citizen of the United States, residing in the city of New York, in the State of New York, 5 have invented a new and useful Wrench, of which the following is a specification.

This invention relates generally to vehicle-wrenches, and more particularly to an attachment to be connected to the ordinary wrench 10 now in use for the purpose of enabling the wrench to fit nuts of different sizes.

With this object in view the invention consists, essentially, of a spring-plate one member of which is adapted to rest within the 15 socket of the wrench, while the other member is provided with a clip adapted to engage the shank of handle portion of the wrench, thereby holding the attachment in its proper relative position.

20 The invention consists also in certain details of construction and novelties of combination, all of which will be fully described hereinafter and pointed out in the claims.

In the drawings forming part of this specification, Figure 1 is a perspective view of a wrench constructed in accordance with my invention. Fig. 2 is a vertical longitudinal section of a portion of the wrench. Fig. 3 is a transverse section on the line 3-3 of Fig. 2 30 looking in the direction of the arrow. Fig. 4 is a detail perspective view of my invention detached from the wrench.

In carrying out my invention I employ an ordinary socket-wrench A, having an essentially 35 rectangular-shaped socket B at one end, while the opposite end is constructed in the usual manner to provide a series of different-sized sockets. The great difficulty with wrenches of this kind has been that the small 40 sockets at the rear end of the shank were too small for the average-sized vehicle-nut and the large socket at the forward end was often too large. In order, therefore, to remedy this defect and at the same time provide an attachment which will securely hold the nut in 45 place in the socket after it has been unscrewed, I have devised my attachment, which, broadly speaking, consists of a spring-metal strip or 50 plate C, bent in the shape of a V at C', the short end C² projecting up into the socket, from the rear side of the same, while the longer

member C³ extends rearwardly and upwardly to the bottom of the shank. A spring-clip C⁴ is constructed upon the upper end of the member C³, which spring-clip is of such size and 55 shape that it will readily embrace the shank and securely hold the attachment in place, the rear wall of the wrench fitting in the angle C' of the spring-plate. The clip C⁴, it will be understood, is formed by constructing a lateral extension at the top of the spring-plate and bending the same back upon itself, as most 60 clearly shown in Fig. 4, and the clip can be corrugated or shaped to correspond with the shape of the shank, thereby insuring a close 65 fit. By having the spring-tongue C² projecting into the socket B it will be readily understood that whenever the socket is placed upon the nut to be unscrewed the spring-tongue will be pressed back toward the rear 70 wall, and the wrench is then operated the same as usual. The tension of the spring will always be sufficient to hold the nut within the socket after it has been unscrewed from the bolt or spindle. It will also be understood that a nut smaller than the socket 75 proper can be easily unscrewed and also one of substantially the same size, inasmuch as the spring-tongue can be pressed back flat against the rear wall of the socket, and as 80 this plate is very thin it will be seen that it will take up very little space and not sufficient to prevent a larger-sized nut being accommodated by the socket. It will also be understood that my invention is applicable 85 to all classes of wrenches employing a rigid socket, and by changing the angle of the parts it can be readily adapted to the different constructions of wrenches.

Having thus fully described my invention, 90 what I claim as new, and desire to secure by Letters Patent of the United States, is—

1. A wrench attachment consisting of a spring-metal plate essentially V-shaped in form and having a spring-clip at its upper 95 end adapted for engagement with the shank of the wrench, substantially as shown and described.

2. A wrench attachment, consisting of a spring-metal plate, essentially V-shaped in 100 form, the shorter arm being adapted to rest within the socket of the wrench, and the longer

arm having a spring-clip at its upper end adapted to engage the shank of the wrench, substantially as shown and described.

3. The combination with a wrench having a shank and rigid socket, of the essentially V-shaped spring-metal plate having a spring-clip at its upper end, said spring-clip being adapted to engage the shank of the wrench, the

free end of the spring-metal plate projecting forwardly and into the socket of the wrench, substantially as shown and described.

ADAM E. KARSNER.
